UNITED STATES PATENT OFFICE.

JOHN F. SHELTON, OF FORT WORTH, TEXAS.

DESIGN FOR A POST FOR FENCES.

No. 39,273.

Specification for Design.

Patented April 21, 1908.

Application filed September 4, 1906. Serial No. 333,274. Term of patent 7 years.

To all whom it may concern:

Be it known that I, JOHN F. SHELTON, a citizen of the United States, residing at Fort Worth, Texas, have invented a new, original, and ornamental Design for Posts for Fences, of which the following is a specification, reference being had to the accompanying drawing, forming part thereof.

The figure of drawing is a perspective view showing my new design.

I claim—

The ornamental design for a post for fences, as shown.

JOHN F. SHELTON.

Witnesses:

B. W. MARLIN,
A. L. JACKSON.
